UNITED STATES PATENT OFFICE.

EUGENE F. O'NEILL AND ELMER L. KERN, OF MINNEAPOLIS, MINNESOTA.

NEEDLE VENDOR IN THE FORM OF A MINIATURE PHONOGRAPH.

Application filed May 26, 1924. Serial No. 715,843.

This invention relates to a sales device or display device for the accessory of a machine such as a phonograph. While the invention might be used with various articles and machines, one particular use therefor is for displaying phonograph needles. Phonograph needles are now generally sold by the same dealers who sell the phonographs. The needles are not prominently displayed, as a rule, and it is often the case that the users of phonographs are without needles and are not reminded to purchase needles on account of the fact that the needles are not prominently displayed in the stores.

It is an object of this invention to provide a device in the form of a miniature phonograph, or other machine, which device can be placed on the counter of a drug store or other store and which will carry therein and prominently display phonograph needles or other necessary accessories of the machine. Such needles or other accessory will thus be conveniently handled and displayed in other stores than those which handle the machines and will be accessible in neighborhood drug stores and similar stores in outlying residence sections.

It is a further object of the invention to provide such a device in the form of a miniature phonograph having supporting legs, which legs are also arranged to support the receptacle carrying the accessory or the needles.

These and other objects and advantages of the invention will be fully set forth in the following description made in connection with the accompanying drawings in which like reference characters refer to the same parts throughout the different views, and in which,

Fig. 1 is a view in perspective of the device;

Fig. 2 is a transverse vertical section taken substantially on the line 2-2 of Fig. 1, as indicated by the arrows;

Fig. 3 is a horizontal section through one end of the device, taken on the line 3-3 of Fig. 1, as indicated by the arrows;

Fig. 4 is a vertical section taken on the line 4-4 of Fig. 1, as indicated by the arrows;

Fig. 5 is a horizontal section of one corner of the device taken substantially on the line 5-5 of Fig. 2, as indicated by the arrows; and

Fig. 6 is a perspective view of one of the leg members used.

Referring to the drawings, in Fig. 1 is shown a device in the form of a modern console type of phonograph or talking machine comprising the body portion 1 and the leg members 2. The exterior of the body portion 1 will be colored, finished or embossed to represent the highly finished wood of an actual standard talking machine. The body 1, however, is quite small and forms in effect a miniature talking machine, the same being in one commercial size substantially ten inches long and six inches wide. While the body 1 may be formed in any suitable manner, in the embodiment of the invention illustrated, the same is formed from one blank of sheet material, the bottom portion 1^a being rectangular in form and having the side portions 1^b folded upwardly therefrom. The bottom portion 1^a also has an upwardly folded end portion 1^c at each end thereof. The side portions 1^b have rectangular portions 1^d at each end thereof which fold across the end of a box 80 in superposed adjacent relation and at the outer side of the end piece 1^c. The layers 1^e and 1^b are glued or secured together in any suitable manner but are free adjacent the corners of the box. A hinged lid or cover 3 is provided hinged along one of the sides 1^b by a flexible strap 3^a suitably glued, or otherwise connected to said side and the cover. A handle-equipped crank 4 is provided which projects at one end of the body 90 1 and simulates the usual motor crank on the standard talking machine. The crank is journaled in the outer sheet 1^d and disposed between the same and the inner end piece 1^c. The crank has an inner arm 4^a 95 thereon connected by a link 5 to the underside of the cover 3 adjacent its hinged edge. The said cover can thus be lifted by a turning movement of the crank 4.

The legs 2 have lower portions which are illustrated as in the form of the well known French leg and these portions are provided with an angular flange 2^a from which rises the portion 2^b comprising an integral strip having its sides disposed at 105 right angles. One of the sides of the portion 2^b terminates in a round tongue 2^c, while the other side terminates in a similar round tongue 2^d which, however, is bent downwardly substantially at a right 110

angle along side of the tongue 2^a. The portion 2^b of the leg is disposed in the body 1 at one corner thereof with the outer sides of the portion 2^b contacting the side 5 1^b of the said body and the outer end piece 1^a, respectively, the bottom 1^a being provided with a right angle slot accommodating the portion 2^b, as shown in Fig. 3. At the other corner, the leg portion 2^b is 10 disposed in the body and contacts the other side 1^b and the inner end piece 1^a, as shown in Fig. 5. The side portions 1^b and the end portions 1^a rest upon the flange 2^a and these flanges on the legs thus support 15 the body 1. The bent-over tongue 2^a is thus disposed along side of the end piece 1^c and these folded over tongues 2^a formed the support for a rectangular tray 6 disposed in the upper portion of the body 1 20 directly under the cover 3. The tray 6 is divided by transverse partitions 6^a into a plurality of longitudinal pockets which are adapted to carry the needle packages 7. The packages 7 containing different 25 kinds of needles may be separated in the compartments of tray 6 by transverse partitions 8, if desired. Also a chamber 1^e is thus formed in the body 1 below the tray 6 and this chamber can conveniently 30 be utilized for holding unopened packages of the needle containers 7. A needle may be mounted and displayed at the top of one or more portions 8, showing the type of needle in the adjacent compartment.

35 In operation, the device which, as stated, will be nicely finished and ornamented, and preferably embossed to simulate an actual phonograph will be placed on the store counter. It will obviously attract attention.

40 The cover 3 normally will be elevated and the various kinds of styles of needles in the packets 7 thus prominently displayed. The display of the needles to the many 45 customers visiting the store will result in many sales thereof and persons in need of needles will be reminded to purchase the same. At the same time, the various types and styles of needles will be called to the 50 attention of the customers. If desired, the cover 3 may be kept normally closed and a direction card placed adjacent the de-

vice directing the customer to turn the crank 4. Upon doing so, the needles will be called to his attention.

From the above description it is seen that 55 applicant has provided a simple and ingenious device for displaying and selling the machine accessories or needles. There is, of course, an intimate relation between the device representing a miniature phonograph 60 and the needles used on a phonograph. The invention could also be embodied in a cabinet or casing, such as used in modern radio sets and the tray 6 used to display crystals or other radio parts. The device is quite 65 simple and easily and inexpensively produced and has great utility in connection with the sale of the articles intended.

It will, of course, be understood, that 70 various changes may be made in the form, details, arrangement and proportions of the parts without departing from the scope of applicant's invention, which, generally stated consists in a device capable of carrying out the objects above set forth, such 75 as shown and described and set forth in the appended claims.

What is claimed is:

1. A sales display device for the necessary accessory parts of a machine, such as 80 a phonograph, comprising a substantially rectangular casing having one side thereof formed of a plurality of layers of sheet material, said layers being loose adjacent the corners of said casing, legs having portions 85 of angle shape in cross section disposed in said casing, one side of said portions being disposed between said layers and the other side being disposed along the adjacent side of said casing, one of said sides 90 of said portions having a bent-over end, and a tray in said casing supported on said bent-over ends.

2. The structure set forth in claim 1, said 95 leg members having integral projecting shoulders formed thereon on which the sides of said casing rest, whereby said casing is supported on said legs.

In testimony whereof we affix our signatures.

EUGENE F. O'NEILL.
ELMER L. KERN.
